PNEUMATIC TOOL

Martin D. Hoza, Houston, Tex., assignor to Reed Roller Bit Company, Houston, Tex., a corporation of Texas
Filed Feb. 20, 1961, Ser. No. 90,395
6 Claims. (Cl. 91—232)

This invention relates generally to pneumatic tools and more particularly to cylinder heads for percussive tools.

An object of this invention is to provide a new and improved pneumatic tool useful for removing paint, rust and scale from surfaces.

Another object is to provide a new and improved removable cylinder head for a pneumatic tool.

Another object is to provide a new and improved means for securing a cylinder head to the body of a pneumatic tool.

Another object is to provide a pneumatic tool structure which is economical to manufacture and easy to service and maintain.

Another object is to provide a resilient cylinder head for a percussive tool.

Other objects will become apparent from the following description and accompanying drawings, in which:

FIG. 1 is a side elevational view, partly in section, of an elastic pressure fluid operated, multiple piston tool embodying the invention.

FIG. 2 is a sectional view taken along line 2—2 in FIG. 1.

FIG. 3 is a sectional view taken along line 3—3 in FIG. 1.

FIG. 4 is a sectional view taken along line 4—4 in FIG. 2.

Referring to the drawings, a multiple piston scaling tool is shown generally at 1 comprising an aluminum alloy body 2 having a plurality of cylinders 3. The cylinder 3 has a larger bore 4 and a smaller bore 5. A steel piston 6 is disposed in each of said cylinders 3. The upper end of the piston 6 fits within the larger bore 4 and the lower end of the piston 6 fits within the smaller bore 5. The lower portion of the piston 6 terminates in an end 7 which is adapted to do work on a surface.

A resilient, or plastic, cylinder head 8 which may be made of synthetic rubber, or other suitable plastic material, is secured in the upper end of the cylinder 3. The cylinder head 8 may have a diameter which is slightly larger than the diameter of the bore 4 so that it may be pressed into the bore 4 to seal the upper end of the cylinder 3. The cylinder heads 8 have holes 9 transversely therethrough, and the body 2 has holes 10 extending therethrough and registering with the holes 9 of the cylinder heads 8 as shown in FIG. 1. A securing pin 11 having a diameter slightly larger than the diameter of the holes 9 is inserted through the holes 10 of the body 2 and the holes 9 of the cylinder heads 8 to secure the cylinder heads 8 within the cylinders 3. Since the cylinder heads 8 are made of resilient material and the holes 9 are smaller in diameter than the diameter of the pin 11, the pin 11 is held axially in place by friction.

A hollow handle 12 is threadedly secured in the inlet 13 of the body 2. The other end of the handle 12 may be attached to a valve 14 which communicates with a suitable source of motive power such as compressed air. The body 2 has an alternate inlet 15 which is sealed by a plug 16. If desired, the handle 12 may be secured in the inlet 15 whereupon the plug 16 would then be used to seal the inlet 13. The head 2 has an air inlet passageway 17, one end of which may be sealed by plug 18. The inlet passageway 17 communicates with the inlet 13 through port 19.

In operation, an elastic pressure fluid, usually com-

2

pressed air, is admitted through the valve 14 and hollow handle 12 into the inlet 13, through the port 19 and into the inlet passageway 17 which communicates with the lower portions 20 of the cylinders 3. The fluid pressure in the portion 20 is maintained close to operating pressure so long as the valve 14 is open. The portions 20 communicate with live air ports 21. The exhaust port 22 communicates with exhaust 23, and the port 21 serves to admit high pressure fluid to the upper surface 24 of the piston 6. As shown in FIG. 2, when the exhaust port 22 is closed by the piston 6, the live air port 21 is open thus admitting high pressure fluid to the surface 24 of the piston 6. The shoulder 25 of the piston 6 is also exposed to the same air pressure. Since the piston 6 has a larger area at 24 than the area of the shoulder 25, the piston 6 will then move down to a position shown by the dotted lines as indicated at 6'. As the piston 6 moves down, the exhaust port 22 is opened and the live air port 21 is closed allowing the fluid pressure acting on the piston surface 24 to drop to zero. The pressure acting on the area of the shoulder 25 then moves the piston 6 to the "up" position, closing the exhaust port 22 and again opening the live air port 21 to admit high pressure fluid to the surface 24 of the piston 6 for the next cycle.

As the piston 6 reciprocates within the cylinder 3, it may come into contact with the cylinder head 8. Since the cylinder heads 8 are made of a resilient or plastic material, they serve to cushion the impact of the piston 6 whereupon the battering effect of such impacts on the pistons 6 and the walls of the cylinders 3 is alleviated. It will be apparent that the cylinder heads 8 may be easily removed in order to change the pistons 6 or to service the tool. The cylinder heads 8 being frictionally secured within the cylinder 3 and upon the securing pin 11 are not easily vibrated loose. The cylinder heads 8 may be molded or otherwise formed, thus providing a relatively inexpensive cylinder head which does not require close manufacturing tolerances to effect a fluid-tight seal for the upper end of the cylinder 3. Actual operations indicate that the tool of the invention provides longer useful tool life, and is easily serviced for maintenance or to replace the pistons 6.

The invention is not limited to the embodiment shown. Various changes within the scope of the following claims will occur to those skilled in the art.

I claim:

1. An elastic pressure fluid operated percussive tool comprising a body having a plurality of cylinders, each cylinder having a bore of two diameters, a piston in each of said bores having an upper portion fitting the larger portion of said bore and a lower portion fitting the smaller portion of said bore and extending therethrough outwardly from said body and terminating in an end adapted to work on a surface, the said body having passages controlled by said piston for admitting and exhausting pressure fluid to cause the pistons to reciprocate within said cylinders, a synthetic rubber cylinder head in the upper end of each of said larger bore portions to seal the same, each of said resilient cylinder heads having a hole transversely therethrough, the said body having holes therethrough registering with said cylinder head holes, a single pin extending through said holes in said body and cylinder heads, the said pin having a diameter larger than the diameter of said cylinder head holes.

2. A fluid operated percussive tool comprising a body having a plurality of cylinders, each cylinder having a bore of two diameters, a piston in each of said bores having an upper portion fitting the larger portion of said bore and a lower portion fitting the smaller portion of said bore and extending therethrough outwardly from said

body and terminating in an end adapted to work on a surface, the said body having passages controlled by said piston for admitting pressure fluid to cause the pistons to reciprocate within said cylinders, a plastic cylinder head in the upper end of each of said larger bore portions to seal the same, each of said resilient cylinder heads having a hole transversely therethrough, the said body having holes therethrough registering with said cylinder head holes, a single pin extending through said holes in said body and cylinder heads, the said pin having a diameter larger than the diameter of said cylinder head holes.

3. A fluid operated tool comprising a body having a cylinder, said cylinder having a bore of two diameters, a piston in said bore having an upper portion fitting the larger portion of said bore and a lower portion fitting the smaller portion of said bore and extending therethrough outwardly from said body and terminating in an end adapted to work on a surface, the said body having passages controlled by said piston for admitting and exhausting pressure fluid to cause the piston to reciprocate within said cylinder, a resilient cylinder head in the upper end of said larger bore portion to seal the same, said resilient cylinder head having a hole transversely therethrough, the said body having holes therethrough registering with said cylinder head hole, a pin extending through said holes in said body and cylinder head, the said pin having a diameter larger than the diameter of said cylinder head hole.

4. A fluid operated tool comprising a body having a cylinder, said cylinder having a bore of two diameters, a piston in said bore having an upper portion fitting the larger portion of said bore and a lower portion fitting the smaller portion of said bore and extending therethrough outwardly from said body and terminating in an end adapted to work on a surface, the said body having passages con-

25 trolled by said piston for admitting pressure fluid to cause the piston to reciprocate within said cylinder, a resilient cylinder head adapted to be pressed into the upper end of said larger bore portion to seal and close the same and means for retaining said resilient cylinder head within the larger bore portion of said cylinder.

5 5. A tool comprising a body having a cylinder, a piston in said cylinder having a lower end extending outwardly from said body and terminating in an end adapted to work on a surface, a resilient cylinder head adapted to be pressed into the upper end of said cylinder to seal and close the same and means for retaining said resilient cylinder head within said cylinder.

10 6. An elastic pressure fluid operated tool having a body, said body having a cylinder, a piston adapted to reciprocate in said cylinder, the said piston having one end extending from the lower portion of said cylinder, and a plastic cylinder head adapted to be pressed into the other end of said cylinder and providing the sole means for closing and sealing said end of said cylinder and means for retaining said head within said other end of said cylinder.
